WINDER CONTROL SYSTEM

Frank C. Fennell, Greensburg, Pa., assignor to
Westinghouse Electric Corporation, East Pittsburgh, Pa., a corporation of Pennsylvania

Application September 19, 1947, Serial No. 775,069

13 Claims. (Cl. 242—80)

1

My invention relates to electric control systems for winding flexible material, such as textile, wire, rubber or plastics.

It is known, in connection with wire insulating machines, to provide for the processed wire material a take-up stand with two exchangeable reels or spools so that when one reel is full, the running material is transferred to the other reel and thereafter cut between the two reels so that the full reel can be replaced by an empty one while the other reel is being filled. In these known machines, the two reels, when running simultaneously during the transfer period, are driven by a single motor which is controlled by a variable-voltage (Ward Leonard) system to maintain substantially constant winding tension. Mechanical clutch devices or the like controllable transmission means are provided to couple the motor with either reel or with both reels during the various stages of the winding and transfer operations.

It is an object of the invention to provide an electric control system, generally of the kind above-mentioned, that eliminates the need for mechanical clutches or the like devices and secure an operation of improved smoothness and a higher degree of controllability.

To this end, and in accordance with my invention, I equip each reel to be driven with a separate drive motor and provide the motors with respective control means that are electrically interlinked to operate the reels during the transfer periods in the proper relation to each other to permit transferring the winding material from the full reel to the empty reel under maintenance of optimum running conditions.

In accordance with another feature of the invention, subsidiary to the one above-mentioned, I energize both or all motors of the multiple winding device from a single generator and regulate the motors for constant winding tension with the aid of a single regulating generator.

According to another and more specific feature of the invention, I provide each motor of a double winding device with a control field winding and cross-connect the control field windings of the two winder motors during the transfer period so that the two motors are effective to impose a speed matching control upon each other.

These and other objects and features of the invention will be apparent from the following description of the embodiment illustrated in the drawing in which:

Figure 1 shows schematically the two reels of

2

a double windup stand, while Figure 2 shows diagrammatically the windup stand with the associated control devices and the appertaining electric control system.

5 In Figure 1 the material to be wound is denoted 1. This material may consist of a wire or thread which comes from a fabricating machine or equipment and passes between rollers 2 through a guide 3, guide 3 is reciprocable along 10 a structure 4 in order to place the wire properly on one of the two reels denoted by 10 and 110. In the illustration of Figure 1, it is assumed that the material 1 was previously wound onto the reel 10 and that this reel is filled and ready to be 15 removed from the stand. In order to permit a continuous operation of the fabricating machinery that supplies the material 1, the material is transferred to the empty reel 110 before the woundup material is cut off. In order to effect 20 the transfer a loop of material is pulled manually or by automatic means; and this loop, denoted by L is placed in contact with the core portion of reel 110 which is running at that time. As soon as the material 1 is caught by reel 110, 25 a knife K is moved into the path of the material portion between the two reels so that the material is cut at this place. From then on, the guide 3 operates to lead the material 1 onto the reel 110 which continues its winding operation while 30 the full reel 10 is removed from the stand and replaced by an empty one. When the reel 110 is filled, the material 1 is transferred back to the empty reel 10, etc.

At the instant the material 1 is transferred 35 from the full to the empty reel, both reels must be operating at the same rotational speed. Otherwise, the empty reel would unwrap the material from the full reel. However, as soon as the material is properly attached to the empty 40 reel and cut from the portion wound up on the full reel, the empty reel must be speeded up because the material on the empty reel has initially a much smaller diameter than that on the full reel and hence is running too slow in linear feet per minute as compared with the speed at 45 which the material is supplied from the fabricating machinery.

The control system according to the invention has two separate motors for driving the respective reels 10 and 110 and these motors are so controlled that the speed of each reel, during its normal winding performance, is regulated for substantially constant winding tension. During the above mentioned transfer period, however, 55 the control system operates to run both motors

Figure 1 shows schematically the two reels of

3

at the same speed and preferably at a speed value sufficiently reduced for a satisfactory transfer operation. After the material is cut between the two reels, the system operates to automatically accelerate the drive motor of the empty reel up to the normal speed and then continues to regulate this speed for constant winding tension.

The means for achieving the just-mentioned control performance will be described presently with reference to Figure 2. According to Figure 2, the shafts on which the two reels 10 and 110 are exchangeably accommodated are driven through respective mechanical connections, here schematically represented by dash lines 11 and 111 respectively, from the armatures 12 and 112 of two respective direct current motors M1 and M2, each having three field windings denoted by 13, 14, 15 and 113, 114, 115, respectively.

The two motors are provided with two inter-linked control systems. The elements of the control system appertaining to motor M1 are denoted by numerals between 16 and 53. The corresponding elements of the control system appertaining to motor M2 are denoted by the same reference numerals except that the prefix 1 is added. For instance, the element 117 of the control system for motor M2 corresponds in design and function to the element 17 of the control system for motor M1. Consequently, only the control system for motor M1 need be described in detail, the description being immediately applicable to the control system for motor M2 if the just-mentioned difference in the reference numerals is observed.

Energization for both motors is supplied from the armature 5 of a main generator G whose field winding 5' is separately excited from a suitable source of constant voltage (not illustrated). The speed regulation of both motors is effected by means of a regulating generator R whose armature 6 is under control by three field windings 7, 8 and 9. The field winding 7 provides self-excitation. It is shown to be serially connected in the circuit of armature 6 although a shunt or compound field may be used instead. A calibrating resistor in the circuit of field winding 7 is denoted by 7'.

The control system for motor M1 includes several relays or contactors CM1, C1, CR1, A1, B1 and a limit switch S1. The corresponding devices of the control system for motor M2 are denoted as a whole by CM2, C2, CR2, A2, B2 and S2 respectively.

Relay CM1 has a control coil 17 for actuating four contacts 18, 19, 20 and 21. Relay C1 is a timing relay which picks up when its main coil 24 is excited and drops off when an adjusted timing period has elapsed after the coil 24 is deenergized. The timing period can be adjusted within limits by varying the excitation of a neutralizing coil 23. The appertaining relay contacts are denoted by 25 and 26.

Relay CR1 has a control coil 27 for actuating two contacts 28 and 29. Relay A1 is an accelerating contactor. Its coil 31 actuates three contacts 32, 33 and 34.

Relay B1 is a timing relay of an electromagnetic design similar to that of relay C1. The neutralizing coil of relay B1 is denoted by 35. The main coil 36 of relay B1 actuates three contacts 37, 38 and 39.

The armature circuit of motor M1, as well as the control coils of the above-mentioned relays, are energized from the positive and negative

4

mains P and N of generator G. The energization of the motor armature circuit and of the relay coil circuits is switched in by a normally open start contact 41, and the energization is ultimately interrupted by the actuation of a normally closed stop contact 42.

The limit switch S1 has two contacts 43 and 44 actuated by a roller 45 or feeler element which contacts the material wound up on reel 10. Contacts 43 and 44 close only when the reel is filled with material and ready to be taken off the stand.

The control system for motor M1 includes also a group of resistance devices. A rheostat 51 serves to provide adjustable excitation for the neutralizing coils 23 and 35 of relays C1 and B1 respectively, in order to permit a calibration of the timing periods of these relays. A tapped resistor 52 is series connected with the armature 12 of motor M1 and serves as a starting resistor. A rheostat 53 is series connected with the motor field winding 13. This field winding serves to limit the motor speed and the limiting effect can be adjusted by means of the rheostat 53.

The above-mentioned elements of the control system for motor M1 are duplicated in the system for motor M2 as mentioned. There are, however, some additional devices which are common to both systems. A resistor 54 is connected in parallel to the pilot field winding 8 of the regulating generator R under the joint control of contacts 20 and 120 in relays CM1 and CM2. Also common to both systems are two resistors 155 and 156 and an appertaining control relay T whose contacts 157, 158 and 159 of relay T are controlled by a coil 160 whose circuit is jointly controlled by contacts 48 and 148 of the cut control device D.

The device D for controlling the knife K is shown to have two push buttons 46 and 146, each of which controls an electromagnetic device (not illustrated) for moving the knife K into the path of the loop of material that extends from the full to the empty reel during the transfer period. Button 46, when actuated, also causes two contacts 47 and 48 to open. When contact 146 is actuated, the corresponding contacts 147 and 148 are opened.

The operation of the winder drive is as follows. The system is set into operative condition by driving the armatures 5 and 6 of generators G and R at constant speed. As customary, both generators may be mounted on a common shaft and driven by a constant speed motor. If desired, the same shaft may also carry the armature of an exciter for providing the constant voltage needed for the generator field winding 5'.

With the motor generator set running, the generator mains P and N are energized.

Assuming that the winder is at rest and that the reel 10 is to be started first, the operation is initiated by actuating the start contact 41. This contact then closes for coil 27 of relay CR1 the circuit:

P—41—42—147—27—N (1)

Relay CR1 picks up and closes a self-holding circuit at contact 28 which shorts the start contact 41. Consequently, the performance continues even when the start contact 41 is thereafter released. Contact 29 of relay CR1 places excitation on the speed limit field winding 13 of motor M1 in the circuit:

75 P—29—13—53—N (2)

Contact 28 of relay CR1 closes for coil 36 of timing relay B1 the circuit:

P-28-33-36-N (3)

Relay B1 picks up. Its contact 38 closes for coil 24 of timing relay C1 the circuit:

P-28-61-38-24-N (4)

Relay C1 picks up and at contact 26 closes for coil 31 of accelerating relay A1 the circuit:

P-28-61-38-37-26-18-31-N (5)

Relay A1 picks up and closes the motor armature the circuit:

P-12-52-34-N (6)

The entire starting resistor 52 is serially included in the armature circuit (6) because contact 39 of timing relay B1 is open. The motor M1 starts accelerating. Contact 33 is now open and the coil circuit (3) of timing relay B1 is interrupted. Hence, after the elapse of a timing period determined by the excitation of the neutralizing coil 35, relay B1 drops out and its contact 39 shorts part of resistor 52 for increased acceleration of motor M1. Relay A1 remains in because its contact 32 closes the holding circuit:

P-28-61-32-18-31-N (5a)

When timing relay B1 drops out, its contact 38 opens the coil circuit (4) of relay C1. After the elapse of its timing period, relay C1 drops out and its contact 25 closes for coil 17 of relay CM1 the circuit:

P-28-61-32-25-17-N (7)

Contactor CM1 picks up. Its contact 18 opens the coil circuit (5a) of relay A1. Relay A1 drops out. Its contact 34 opens the armature circuit (6), but a new armature circuit excluding the entire starting resistor 52 is now established through contact 21 of relay CM1:

P-12-62-115-63-21-64-8-N (8)

This circuit extends through the control field 115 of motor M2 although the latter is not running at this time. The circuit (8) also extends through the pilot field winding 8 of the regulating generator R. This provides for generator R a control component proportional to the armature current of motor M1. It will be understood that instead of connecting the pilot field winding 8 directly in the motor armature circuit, some other circuit connection may be used to render the excitation of pilot field winding 8 proportional to the armature current. For instance, a fixed resistor may be series connected in the armature circuit, and pilot field winding 8 may be connected across the resistor so that the voltage drop imposed on winding 8 is proportional to the current flowing through the fixed resistor.

Motor M1 is now running at the proper speed. Under these conditions, the motor field winding 15 is not excited because the motor M2 is at rest. However, the speed limit field winding 13 is excited and the main control field 14 of motor M2 is excited from the armature 6 of the regulating generator R in the field circuit:

6-16-14-114-106-7'-7-6 (9)

The voltage generated in armature 6 of generator R and effective on the control field winding 14 of motor M2 is due to the resultant excitation of field windings 7, 8 and 9. As mentioned above, the pilot field winding 8 is excited in proportion

to the armature current of motor M1. The pattern field winding 9 is excited in the field circuit:

P-156-158-9-N (10)

5 The pattern field excitation is adjusted at rheostat 156. Field windings 8 and 9 operate differentially so that their resultant field effect is zero when the armature current of motor M1 is in accordance with the adjusted pattern field excitation of winding 9. If the motor armature current departs from the correct value, the resultant field excitation of windings 8 and 9 assumes a finite differential value and its polarity depends upon whether the armature current is above or below the correct value. The resultant differential field effect in regulating generator R is then such as to increase or decrease the voltage generated in the armature 6 so that the excitation of the motor control field winding 15 changes in the direction and to the extent needed to reestablish the proper current value. As a result, the motor speed adjusts itself to the value necessary for maintaining a substantially constant armature current. Under this operating condition, the torque of the driven reel varies in dependence upon the speed variation of the motor so as to maintain constant in the winding material. In other words, due to the control effect of the regulating generator R, the reel when empty operates at a higher speed of revolution than when it is filled so as to maintain a constant linear speed of the material 1.

20 The self-excited field winding 7 of regulating generator R does not immediately participate in the just-mentioned control performance but serves to provide a high amplification factor. By a proper selection or adjustment of the resistor 7', the resistance line of the self-excited field circuit is adjusted to be approximately coincident with the initial linear portion of the magnetic or no-load characteristic of the generator R. Consequently, the self-excitation provided by field winding 7 has the tendency to maintain the output voltage of generator R at any otherwise adjusted value along the linear portion of the characteristic. Hence, the two field windings 8 and 9 are merely called upon to provide the slight additional control effect needed to shift the operating point of the generator up or down along its characteristic. Therefore, minute changes in the differential field excitation provided by windings 8 and 9 are sufficient to cause relatively large voltage changes to occur across the generator armature 6.

25 When the reel 19 is nearly filled with material, the limit switch S1 operates to prepare the system for the transfer of the material 1 to reel 110. Roller 45, moving upwardly, closes the contacts 43 and 44. Contact 44 lies electrically in parallel to the start contact 141 for motor M2. Consequently, the closing of limit contact 44 establishes 30 for coil 127 of relay CR2 the circuit:

P-44-161-142-47-127-N (11)

35 Relay CR2 picks up and closes the self-holding circuit:

P-128-161-142-47-127-N (11a)

40 while energizing the speed limit field 113 of motor M2 in circuit:

P-129-113-153-N (12)

45 Coil 136 of B2 is energized in the circuit:

P-128-133-136-N (13)

Relay L picks up. Its contact 138 closes the following circuit for coil 124 of C2:

P—128—161—138—124—N (14)

Relay C2 picks up. Its contact 125 closes for coil 131 of relay A2 the circuit:

P—128—161—138—137—126—118—131—N (15)

Accelerating relay A2 picks up and closes for motor M2 the armature circuit:

P—112—152—134—N (16)

with the resistor 152 serially included. Motor M2 starts running. Since contact 133 of relay A2 is now open circuit (13) is interrupted so that relay B2 drops out after elapse of its timing period. Contact 139 of relay B2 now shorts part of resistor 152 for further acceleration of motor M2. Relay A2 stays in because its contact 132 closes the self-holding circuit:

P—128—161—132—118—131—N (15a)

At the moment relay B2 drops out, its contact 138 opens the coil circuit (14) of relay C2. Hence, after elapse of another timing period, relay C2 drops out and closes, at contact 125, the following circuit for coil 117 of relay CM2:

P—128—161—132—125—117—N (17)

Relay CM2 picks up. Its contact 118 opens the coil circuit (15) of relay A2. Relay A2 drops out. Its contact 34 opens the armature circuit (16) of motor M2, but a new armature circuit is now established, under exclusion of the starting resistor 152; through contact 121 of relay CM2:

P—112—162—15—163—121—64—8—N (18)

It will be noted that before the circuit (18) is established, the armature connection of motor M2 is separate from the pilot field winding 8 of the regulating generator, and also separate from the control field winding 15 of motor M1. Consequently, the operation of motor M2 during its accelerating period, i. e., the starting current of motor M2, does not affect the operation of the motor M1. Only when motor M2 has accelerated, is the circuit (18) effective to energize the field winding 15 in motor M1 and to impose a control effect on the pilot field winding 8 of generator R. Under these operating conditions, both motors are equally controlled by the regulating generator and impose a mutual control upon each other due to the cross-connected field windings 15 and 115. Consequently, both motors are now regulated to operate at the same speed. This speed is automatically reduced to a value conveniently low for transferring the material from the full to the empty reel. The speed reduction is due to the fact that when relay CM2 closes, its contact 120 places the resistor 54 in shunt with the pilot field winding 8 of generator R which increases the excitation of motor field windings 14 and 114. The shunt resistor circuit extends between the elements 64 and N of circuit (18) and in parallel to the field winding 8 as follows:

64—20—120—54—N (18a)

The transfer of the material from reel 10 to reel 110 is now effected, as described above, by throwing a loop over to reel 110 until the material is firmly secured to reel 110 and then actuating the knife K of the cutting device D. This is preferably done by fully automatic means that operate in dependence upon the completion of circuits (18) and (18a). However, since the automatic means are not essential to the invention

proper, they are not illustrated, and, for explaining the invention, it may just as well be assumed that the loop L (Fig. 1) is pulled by manual means and that then the operator pushes the button 146 at the empty-reel side of device D.

Actuation of button 146 causes a solenoid (not shown) to operate and to move knife K until it cuts the material. Simultaneously, the contacts 147 and 148 are lifted and opened. Contact 147 opens the coil circuit (1) of relay CR1 which drops out and opens contact 28 so that the coil circuit (7) of relay CM1 is also interrupted. Relay CM1 drops out. Its contact 21 cuts the armature circuit (8) of motor M1. Motor M1 and reel 10 stop, and the reel can be replaced by an empty one while reel 110 is being filled with material.

As soon as, during the just-mentioned stage, the wire has found a foothold on the empty reel and starts winding on the latter, the load on motor M1 drops and its armature current in circuit (8) drops correspondingly. Since, as explained, the generator R regulates the motor fields 14 and 114 for constant motor armature current, the drop in excitation of pilot field winding 8 in generator R has the effect of weakening the excitation of motor field windings 14 and 114. This causes both motors to accelerate under increase of their armature currents. During this acceleration the cross-connected series field windings 15 and 115 tend to keep the motors in step (the loaded reel has approximately three times the moment of inertia of the unloaded reel).

Relay T and the associated circuits serve to increase the just-mentioned acceleration for shortening the transfer period. During the interval between the closing of contact 43 of limit switch S1 and the subsequent opening of contact 148 of cutting device D, coil 160 of relay T is energized in the circuit:

P—43—48—148—65—160—N (19)

Relay T picks up and, by opening contact 158, inserts the resistor 155 serially into the pattern field circuit (10) instead of the resistor 156 which is now shorted by contact 157. Resistor 155 is rated to recalibrate the pattern field circuit for increased acceleration. As a result, the motor M2 rapidly reaches sufficient speed to again place tension on the material 1. At the moment when relay CM1 drops out to stop motor M1, contact 20 of relay CM1 opens the resistance shunt circuit (18a) of the pilot field winding 8 so that motor M2 assumes normal winding speed, and the speed is then regulated for constant winding tension in the same manner as previously that of motor M1.

The winder can be stopped at any moment by opening the stop contact 42 or 142 of the operating motor. When at rest, the system can be started with motor M2 by actuating button 141.

Control systems according to the invention are applicable for winding devices which require a very wide range of valuable winding speeds, for instance, up to a ratio of 20:1. They are advantageously applicable to various types of fabricating machinery such as wire insulating machines of the continuous vulcanizing type, machines for making plastic tubes, rubber, paper or textile fabricating machinery and the like.

It will be understood by those skilled in the art that winder control systems according to the invention permits various modifications and can be embodied in a manner different from the example specifically illustrated and described in this disclosure without departing from the essence of

my invention and within the essential features set forth in the claims annexed hereto.

I claim as my invention:

1. An electric control system for a continuously operable two-reel winder, comprising two reel drives disposed for alternately taking up the material to be wound and having two respective drive motors, two control systems connected to said respective motors, limit switch means connected with each of said control systems for causing one motor to start operating before the other motor is stopped so that both motors run simultaneously during overlapping intervals of their respective running periods to permit transfer of material from one to the other reel drive during said intervals, and cutting means disposed for severing the transferred material between said two reel drives and electrically connected to said control systems to stop said other motor in dependence upon actuation of said cutting means.

2. An electric control system for a continuously operable two-reel winder, comprising two take-up reel drives each having a motor, two control systems connected to said respective motors and capable of operating each motor independently from the other, two limit devices each associated with one of said respective reel drives and electrically connected with the control system appertaining to the motor of the other reel drive for causing said latter motor to start operating when the reel of said one reel drive is substantially filled, and a cut control device disposed to permit severing material transferred from said one to said other reel drive when said two motors are running simultaneously, said device having contacts electrically connected with said control systems for stopping said motor of said one reel drive when said control device is actuated.

3. An electric control system for a continuously operable two-reel winder, comprising two reel drives disposed for alternately taking up the material to be wound and having two respective drive motors, two control systems connected to said respective motors, limit switch means connected with each of said control systems for causing one motor to start operating before the other motor is stopped so that both motors run simultaneously during overlapping intervals of their respective running periods to permit transfer of material from one to the other reel drive during said intervals, a cut control device disposed for cutting the transferred material between said reel drives and being electrically connected to said control systems to stop said other motor in dependence upon actuation of said device, speed regulating means, and relay means forming part of said control systems and being connected with said limit switch means and with said device for controlling said speed regulating means so as to maintain said two motors at substantially equal speeds during said intervals.

4. An electric control system for a continuously operable two-reel winder, comprising two take-up reel drives each having a motor, circuit means for energizing said motors, two control systems connected to said respective motors for controlling their respective energization from said circuit means, each of said motors having a speed controlling field winding, regulating means having a control circuit and being connected to said field windings for controlling the speed of said motors substantially in accordance with the energizing currents of the respective motors, said control systems having sequence relays interlinked with one another and connected to said circuit

means and to said regulating means for first accelerating each motor and thereafter connecting said regulating means to said field winding of said motor when starting the motor, two limit devices each associated with one of said respective reel drives and electrically connected with the control system appertaining to the motor of the other reel drive for causing said latter motor to start when the reel of said one reel drive is substantially filled, and a cut control device disposed to permit severing material transferred from said one to said other reel drive when said two motors are running simultaneously, said device having contacts electrically connected with said control systems for stopping said motor of said one reel drive in dependence upon actuation of said device.

5. An electric control system for a continuously operable two-reel winder, comprising two take-up reel drives each having a motor, circuit means for energizing said motors, two control systems connected to said respective motors for controlling their respective energization from said circuit means, each of said motors having an armature circuit and field means that comprise a speed control winding, a regulating generator having an armature connected to said speed control windings for providing variable excitation therefor and having control field means connected to said motor armature circuits for controlling said excitation in dependence upon the current in said armature circuits so as to maintain said current substantially at a desired value, said control systems having sequence relays interlinked with one another and connected to said circuit means and to said control field means of said generator for starting each motor while said control field means are disconnected from said armature circuit of the accelerating motor and connecting said control field means to said armature circuit after said motor has accelerated, two limit devices each associated with one of said respective reel drives and electrically connected with the control system appertaining to the motor of the other reel drive for causing said latter motor to start when the reel of said one reel drive is substantially filled, and a cut control device disposed to permit severing material transferred from said one to said other reel drive when said two motors are running simultaneously, said device having contacts electrically connected with said control systems for stopping said motor of said one reel drive in dependence upon actuation of said device.

6. An electric control system for a continuously operable two-reel winder, comprising two take-up reel drives each having a motor, each motor having an armature circuit, a speed-limiting field winding and a control field winding, energizing circuit means, two control systems for connecting said armature circuits and said speed-limiting field windings of said respective motors to said circuit means, speed regulating means having a control circuit and an output circuit, said output circuit being connected to said control field windings of said motors for providing controllable excitation therefor, said control circuit being connected under control by said systems to said armature circuits of said respective motors for controlling said excitation in accordance with the currents substantially constant, said control systems having sequence relays for first energizing said armature circuit and speed-limit field winding of each motor when starting the motor and subsequently connecting said control circuit to said armature cir-

11

cuit of said motor after acceleration of the latter motor to prevent the starting current of said motor from affecting said excitation, two limit devices each associated with one of said respective reel drives and electrically connected with the control system appertaining to the motor of the other reel drive for causing said latter motor to start when the reel of said one reel drive is substantially filled, and a cut control device disposed to permit severing material transferred from said one to said other reel drive when said two motors are running simultaneously, said device having contacts electrically connected with said control systems for stopping said motor of said one reel drive in dependence upon actuation of said device.

7. An electric control system for a continuously operable two-reel winder, comprising two reel drives disposed for alternately taking up the material to be wound and having two respective drive motors, two control systems connected to said respective motors, limit switch means connected with each of said control systems for causing one motor to start operating before the other motor is stopped so that both motors run simultaneously during overlapping intervals of their respective running periods to permit transfer of material from one to the other reel drive during said intervals, each of said motors having an armature circuit controlling field means connected to the armature circuit of the other motor under control by said control systems so that during said intervals said respective field means impose an initial speed-matching control on said motors, and a cut control device disposed for severing the transferred material between said two reel drives and electrically connected to said control systems to stop said other motor in dependence upon actuation of said cutting means device.

8. An electric control system for a continuously operable two-reel winder, comprising two take-up reel drives each having a motor, each motor having an armature circuit, a speed-limiting field winding and two control field windings, energizing circuit means, two control systems having relay means for connecting said armature circuits and said speed-limiting field windings of said respective motors to said circuit means, speed regulating means having a control circuit and an output circuit, said output circuit being connected to one of said control field windings of said respective motors for providing controllable excitation therefor, said control circuit being connected under control by said systems to said armature circuits of said respective motors for controlling said excitation in accordance with the currents in said armature circuits for maintaining said currents substantially constant, said systems having sequence relays for first energizing said armature circuit and speed-limit field winding of each motor when starting the motor and subsequently connecting said control circuit to said one control field winding of said respective motors, two limit devices each associated with one of said respective reel drives and electrically connected with the control system appertaining to the motor of the other reel drive for causing said latter motor to start when the reel of said one reel drive is substantially filled, and a cut control device disposed to permit severing material transferred from said one to said other reel drive when said two motors are running simultaneously, said device having contacts electrically connected with

12

said control systems for stopping said motor of said one reel drive in dependence upon actuation of said device, said control systems being connected to said other control field windings of said motors for connecting said other control field winding of each motor to the armature circuit of the other motor to impose an initial speed matching effect on said motors during the interval of simultaneous running.

9. An electric control system according to claim 6, comprising resistance means disposed in said control circuit of said speed regulating means, a relay disposed for controlling said resistance means and connected to said limit switch means and to said cut control device to control said resistance means limiting the drop in motor speed during the interval of simultaneous operation of said motors.

10. An electric control system for a continuously operable two-reel winder, comprising two take-up reel drives each having a motor, each motor having an armature circuit, a speed-limiting field winding and a control field winding, energizing circuit means, two control systems for connecting said armature circuits and said speed-limiting field windings of said respective motors to said circuit means, a regulating generator having an armature and two initially differential and balanceable control field windings, said generator armature being connected to said control field windings of said motors to provide controllable excitation therefor, one of said generator control field windings being connected to said circuit means to be energized by normally constant voltage, said other control field winding of said generator being connected under control by said systems to said armature circuits of said respective motors for controlling said excitation in accordance with the currents in said armature circuits, said control systems having sequence relays for first energizing said armature circuit and speed-limit field winding of each motor when starting the motor and subsequently connecting said other generator control field winding to said armature circuit of said motor, two limit devices each associated with one of said respective reel drives and electrically connected with the control system appertaining to the motor of the other reel drive for causing said latter motor to start when the reel of said one reel drive is substantially filled, and a cut control device disposed to permit severing material transferred from one to said other reel drive when said two motors are running simultaneously, said device having contacts electrically connected with said control systems for stopping said motor of said one reel drive in dependence upon actuation of said device.

11. A system for winding material, comprising means for exchangeably accommodating two take-up reels, means for supplying material to one of said reels at a time, said supply means and reel accommodating means being disposed relative to each other to permit transferring the material from the full reel to the empty reel, a cutting device disposed for severing the material extending between said reels after the transfer of the material, two drive motors in driving connection with said respective reel-accommodating means, two control systems for operating said respective motors, two limit devices each associated with one of said respective reel accommodating means and electrically connected to the control system appertaining to the motor of said other reel accommodating means for causing said latter means to start operating when the reel

driven by the first operating motor is filled, said cutting device having contact means electrically connected with said control systems so as to stop said first operating motor when, after the transfer of material, said cutting device is actuated.

12. A system for winding material onto reels, comprising a take-up stand having means for exchangeably accommodating two reels in juxtaposition so as to permit transferring material from one to the other reel, a cutting device disposed relative to said stand to permit cutting the material that stands between the reels after a transfer, two electric drive motors connected with said stand for driving the respective reels, two electric control systems connected to said respective motors and having each a start-control limit switch spacially associated with the accommodating means for the reel driven by the other motor so as to start one motor when the reel driven by the other is filled with a given amount of material, each of said control systems having a stop-control contact associated with said cutting device so as to stop said other motor in dependence upon the actuation of said device.

13. A system for winding material onto reels, comprising a take-up stand having means for exchangeably accommodating two reels in juxtaposition so as to permit transferring material from one to the other reel, a cutting device dis-

posed relative to said stand to permit cutting the material that stands between the reels after a transfer, two electric drive motors connected with said stand for driving the respective reels, two electric control systems connected to said respective motors and having each a start-control limit switch spacially associated with the accommodating means for the reel driven by the other motor so as to start one motor when the reel driven by the other is filled with a given amount of material, each of said control systems having a stop-control contact associated with said cutting device so as to stop said other motor in dependence upon the actuating of said device, and speed control means connected with said motors under control by said systems for controlling said motors to operate at substantially the same rotational speed during their intervals of simultaneous operation.
